CLAIM

The ornamental design for a puzzle, as shown and described.

DESCRIPTION

FIG. 1 is a top, right side perspective view of the puzzle in a first configuration, according to the new design.

FIG. 2 is a front elevation view of the first configuration of the puzzle, wherein the rear, top, bottom, right and left side elevation views are a mirror image thereof.

FIG. 3 is a top, right side perspective view of the puzzle in a second configuration; and,

FIG. 4 is a front elevation view of the second configuration of the puzzle, wherein the rear, top, bottom, right and left side elevation views are a mirror image thereof.

1 Claim, 4 Drawing Sheets(56)
